UNITED STATES PATENT OFFICE.

EARL H. MONAHAN, OF HYANNIS, NEBRASKA.

VEHICLE SPRING CONSTRUCTION.

1,272,497.

Specification of Letters Patent. Patented July 16, 1918.

Application filed January 3, 1917. Serial No. 140,407.

To all whom it may concern:

Be it known that I, EARL H. MONAHAN, a citizen of the United States, and resident of Hyannis, in the county of Grant and 5 State of Nebraska, whose post-office address is Hyannis, Nebraska, have invented certain new and useful Improvements in Vehicle Spring Construction, of which the following is a specification.

10 My invention relates to a spring construction and more particularly to a vehicle spring construction.

The primary object of the present invention is to provide means which is arranged 15 on the conventional type of elliptical springs now in use and which will render the springs stronger and will increase the life of the same.

20 A second object of the invention is to provide an attachment for elliptical springs that will greatly increase the resilient qualities of the springs.

Another important object of the invention is to provide an attachment of the 25 above mentioned character which may be used in conjunction with any type of elliptical spring now on the market and which may be quickly and easily applied to the same.

30 Still another object of the present invention is to provide an attachment of the above mentioned character which consists of few parts, is inexpensive to manufacture and which may be placed on the market at a 35 comparatively low cost.

This invention consists of the constructions, combinations and arrangement of parts that will be hereinafter set forth in the following specification and illustrated in 40 the accompanying drawings, in which

Figure 1 is a side view of a conventional elliptical spring having my invention applied thereto.

Fig. 2 is a sectional view on the line 2—2 45 of Fig. 1 and showing my invention in elevation.

On the drawings like characters of reference indicate like parts in all the views.

Referring more particularly to the drawings, the numeral 5 designates a side bar of 50 an automobile chassis and the numerals 6 and 7 designate the sections of an elliptical spring. While I have shown one form of elliptical spring, it is to be understood 55 that any form of spring may be used in conjunction with my invention.

Mounted on the spring section 6 is a rectangular loop or sleeve 8 which carries a set screw 9 that is threaded into engagement with the section 6 to retain the sleeve or 60 loop in position. Extending from opposite sides of the sleeve or loop 8 are laterally extending perforated ears 10.

Arranged on the spring section 7 is a second sleeve or loop 11 which is retained 65 in position by a set screw 12 and also has extending from opposite sides thereof perforated ears 13. Both of these members 8 and 11 are identical in construction. Extending through the perforated ears 10 of 70 the sleeve 8 and through the perforated ears 13 of the sleeve 11 are relatively long rods 14 which are provided upon their upper ends with heads 15 that rest upon the ears 10. These rods extend vertically and upon opposite sides of the sections 6 and 7. Jam nuts 16 are threaded upon the upper ends 75 of the rods 14 and bear against the under face of the ears 10.

Disposed on the rods 14 are expandable 80 springs 16 and 17. The lower ends of the springs 16 bear against the upper face of the ears 13 while the upper ends of the springs 17 bear against the under face of these ears. Nuts 18 are disposed upon the lower ends 85 of the rods 14 and bear against the springs 18. It will be seen that the tension of these springs 17 may be varied by the adjustment of these nuts. Also threaded upon the rods 14 are nuts 19 which bear against the upper 90 ends of the springs 16 by means of which the tension of the springs may be varied. It will be seen that the movement of the section 7 is between the rods 14 and that these rods will prevent this section from moving 95 laterally.

Having described the preferred embodiment of my invention, I desire it understood that the same is susceptible to various alterations and modifications that may fall within 100 the scope of the appended claim.

What is claimed is:

The combination with upper and lower elliptical springs having corresponding ends 105 suitably connected; of a sleeve receiving a portion of the upper elliptical spring and clamped thereto, said sleeve being provided upon its opposite ends with horizontal ears which are rigidly secured thereto and provided with vertical apertures; a second sleeve receiving a portion of the lower elliptical spring and clamped thereto, said 110

second sleeve being provided upon its opposite ends with horizontal ears which are rigidly secured to the sleeve and have vertical apertures; rigid rods vertically disposed upon opposite sides of the elliptical springs and having their upper ends clamped within the vertical apertures in the ears of the first named sleeve, the lower portions of these

rods being arranged to reciprocate within the vertical apertures in the ears of the second named sleeve, compressible coil springs surrounding the rods above and below the last named ears to contact therewith; and adjustable elements carried by the rods to engage the ends of said coil springs.

EARL H. MONAHAN.
